United States Patent Office

Des. 194,518
Patented Feb. 5, 1963

194,518

DISPLAY STAND

Ira Davidoff, Golden Triangle Bldg., Norfolk, Va.

Filed Jan. 18, 1962, Ser. No. 68,370

Term of patent 14 years

(Cl. D80—9)

Fig. 4.

Fig. 2.

The broken-line representation of advertising matter is for purposes of illustration only.

I claim:

The ornamental design for a display stand, as shown and described.
